CLAIM

The ornamental design for an overhead support device, as shown and described.

DESCRIPTION

FIG. 1 is a top-rear-left perspective view of an overhead support device according to the claimed design.

FIG. 2 is a top-rear-right perspective view of the overhead support device.

FIG. 3 is a bottom-rear-right perspective view of the overhead support device.

FIG. 4 is a bottom-front-left perspective view of the overhead support device.

FIG. 5 is a front view of the overhead support device.

FIG. 6 is a rear view of the overhead support device.

FIG. 7 is a right side view of the overhead support device.

FIG. 8 is a left side view of the overhead support device.

FIG. 9 is a top view of the overhead support device.

FIG. 10 is a bottom view of the overhead support device.

FIG. 11 is an enlarged partial bottom-front-left perspective view of area 11 in FIG. 4;

FIG. 12 is an enlarged partial top-front-left perspective view of FIG. 11;

FIG. 13 is an enlarged partial top-front-right perspective view of area 13 in FIG. 2;

FIG. 14 is an enlarged partial top-front-right perspective view of FIG. 13 with the panel removed to show the details behind it; and,

FIG. 15 is an enlarged partial bottom-rear-right perspective view of area 15 in FIG. 3.

The dash-dot-dot broken lines in FIGS. 2–4 and 11–15 illustrate boundaries of the enlarged views that form no part of the claimed design.

1 Claim, 15 Drawing Sheets
